US0D1069957S

(12) **United States Design Patent** (10) Patent No.: **US D1,069,957 S**
(45) Date of Patent: ** Apr. 8, 2025

(54) **GOLF PUTTING PRACTICE DEVICE**

(71) Applicant: **Peter David Westlake**, Shipton Under Wychwood (GB)

(72) Inventor: **Peter David Westlake**, Shipton Under Wychwood (GB)

(**) Term: **15 Years**

(21) Appl. No.: **35/519,983**

(22) Filed: **Dec. 5, 2023**

(80) **Hague Agreement Data**

Int. Filing Date: **Dec. 5, 2023**

Int. Reg. No.: **DM/233885**

Int. Reg. Date: **Dec. 5, 2023**

Int. Reg. Pub. Date: **Feb. 9, 2024**

(51) **LOC (15) Cl.** **21-02**

(52) **U.S. Cl.**

USPC **D21/791**; D21/718; D21/722; D21/789
